UNITED STATES PATENT OFFICE.

FRANK L. KIRK, OF NEW YORK, N. Y., ASSIGNOR TO GORHAM COMPANY, OF NEW YORK, N. Y.,
A CORPORATION OF NEW YORK.

DESIGN FOR A BAG

No. 39,267.

Specification for Design.

Patented April 21, 1908.

Application filed February 27, 1908. Serial No. 418,156. Term of patent 7 years.

To all whom it may concern:

Be it known that I, FRANK L. KIRK, a citizen of the United States, residing at New York city, in the county of New York and State of New York, have invented a new, original, and ornamental Design for Bags, of which the following is a specification, reference being had to the accompanying drawing, forming part thereof.

The figure is a perspective view of a bag showing my new design.

I claim:

The ornamental design for a bag, as shown.

FRANK L. KIRK.
